ALFRED B. BELL, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

BURNER-SUPPORT FOR GAS-RANGES.

1,205,697.

Specification of Letters Patent. Patented Nov. 21, 1916.

Application filed February 27, 1915. Serial No. 11,089.

To all whom it may concern:

Be it known that I, ALFRED B. BELL, a citizen of the United States, residing at Philadelphia, in the county of Philadelphia and State of Pennsylvania, have invented 5 certain new and useful Improvements in Burner-Supports for Gas-Ranges, of which the following is a specification.

My invention relates to burner supports 10 for gas ranges and is an improvement on some of the features of construction shown in my patent burner boxes for gas ranges, Patent No. 1,159,351 granted November 9, 1915. In that patent is disclosed a pressed 15 metal burner-box in which the burners are supported by a transverse bar or bars having downwardly turned ends removably inserted in vertical pockets formed in a lining member of the burner-box. In the patent also 20 the burners are described as each having a tapered downwardly extending lug mounted in a corresponding hole in the burner supporting bar, the burner having supporting surfaces or lugs on each side of the tapered lug mounted in the hole, whereby the 25 burners are located both horizontally and vertically when the same are mounted in position on the supporting bars.

In the present application I will describe 30 and claim an improvement on the structure referred to, whereby not only is the burner given a positive support so that it will not rock, but also the mixing pipe leading to and carrying the burner may be moved suffi- 35 ciently to the left or right to take care of any slight inaccuracies in assembling the parts. This is of advantage since to obtain the best results the mixing pipes of the burners should be maintained quite accu- 40 rately in alinement with the nozzles on the manifold to which they are connected. I attain these results by supporting each burner on a transverse bar having a slot formed on one edge thereof to receive a lug 45 extending downwardly from the bottom of the burner, the burner having a second lug extending downwardly in substantial contact with the opposite edge of the burner supporting bar. The top of the bar is flat 50 and the bottom of the burner in contact with the bar is planed flat so as to give a positive non-rocking support for the burner. The slots in which one of the lugs on each burner

engage are somewhat wider than the lugs to permit the moving of any burner and its 55 mixing pipe slightly to the left or right to establish the correct alinement of the mixing pipe and the nozzle on the manifold upon which it is mounted, while at the same time lengthwise movement of each mixing pipe, 60 when its burner is seated in position, is prevented by the straddling of the supporting bar by the two lugs on the burner.

In order that a clearer understanding of 65 my invention may be had, attention is hereby directed to the accompanying drawings forming part of this application and illustrating an embodiment of my invention.

In the drawings, Figure 1 represents a 70 plan view of a burner-box with burners supported therein, Fig. 2 is an enlarged partial plan view showing the construction of a burner supporting bar and the engagement of a burner therewith, Fig. 3 is a vertical section on line 3—3 of Fig. 1 to the same 75 scale as Fig. 2, and Fig. 4 is a partial enlarged vertical section on line 4—4 of Fig. 1.

Referring to the drawings, the burner- 80 box 1 is illustrated as being provided with a lining member 2, having vertical side walls 3, in which pockets 4 are formed by pressing the metal of the sides inwardly and slitting the metal horizontally above and below the pressed in portion to form integral straps.

The burner supporting bars 5 have down- 85 wardly bent ends 6 removably inserted in the pockets 4. Preferably the horizontal portions of bars 5 are formed with down- 90 wardly extending rear flanges 7. The burner supporting bars 5 have slots 8, preferably square, cut in one edge thereof, this being the front edge when the vertical flange 7 of the bar is located at the rear as illus- 95 trated. The manifold or gas supply pipe 9 is mounted in any suitable manner as by 100 means of brackets such as 10 and is pro- vided with a plurality of stop-cocks 11 hav- 105 ing reduced ends forming nozzles. The mix- ing pipes 12 carrying burners 13 are of the usual construction, the gas receiving ends of the mixing pipes being slipped over and supported by the nozzles of the cocks 11, and provided with air mixing caps, all in the well known manner.

Each burner is provided with a pair of 105 downwardly extending lugs cast on the bot-

tom of the burner, these lugs being adapted to straddle the supporting bar 5 in the manner shown in Fig. 4, when the burner is mounted in position. As there illustrated, 5 the lug 14 of each burner engages in the corresponding slot 8 of its support 5, the other lug 15 of each burner extending downwardly to the rear of flange 7 of the burner support, the distance between a pair of lugs 10 14 and 15 being only slightly greater than the distance between the rear edge of a slot 8 and the rear edge of the bar 5. The bottom of each burner which is adapted to contact the top surface of a bar 5 is planed flat 15 as illustrated at 16 in Fig. 3, so that the burners have positive non-rocking support on the bar. The slots 8 are of a somewhat greater dimension in the direction of the length of bar 5 than the width of lugs 14 20 so that when the burners have been mounted in position the same may be moved a short distance in the direction of the length of the burner support, to properly align mixing devices 12 with the nozzles on the manifold 25 in case of any slight inaccuracy in assembling of the parts. Such adjustment is, of course, not possible when the burners are provided with tapered lugs fitting closely in corresponding holes in the burner support.

30 Having now particularly described my in-

vention, what I claim and desire to protect by Letters Patent is as follows:

In a gas range, the combination of a burner support comprising a horizontal transverse supporting bar having a slot in 35 one edge portion thereof, a manifold, a mixing pipe movably connected to the manifold, and a burner carried by said mixing pipe, said burner having a downwardly extending lug loosely engaging in said slot and a second 40 downwardly extending lug adapted to loosely engage the opposite edge of said supporting bar when the first lug is in the slot, both the top surface of said bar and bottom surface of said burner in engagement 45 therewith being flat and horizontal, said lugs being separated by a distance from front to rear slightly greater than the bearing width of a bar between a slot and the opposite edge of the bar, and said slot being of a slightly greater dimension lengthwise of the bar than the width of the lug seated therein, substantially as set forth.

This specification signed and witnessed this 25th day of February, 1915.

ALFRED B. BELL.
